US0D1061538S

(12) **United States Design Patent** (10) **Patent No.:** **US D1,061,538 S**
(45) **Date of Patent:** **** Feb. 11, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, Los Gatos, CA (US);
Imran Chaudhri, San Francisco, CA (US); **Alan C. Dye**, San Francisco, CA (US); **Dylan Ross Edwards**, San Jose, CA (US); **Christopher Foss**, San Francisco, CA (US); **Chance Graham**, Campbell, CA (US); **Aurelio Guzmán**, San Jose, CA (US); **Jonathan P. Ive**, San Francisco, CA (US); **Chanaka Karunamuni**, San Jose, CA (US)

(73) Assignee: **Apple Inc.**, Cupertino, CA (US)

(**) Term: **15 Years**

(21) Appl. No.: **29/831,469**

(22) Filed: **Mar. 21, 2022**

Related U.S. Application Data

(63) Continuation of application No. 29/815,517, filed on Nov. 15, 2021, now Pat. No. Des. 947,217, which is a continuation of application No. 29/756,983, filed on Nov. 2, 2020, now Pat. No. Des. 942,474, which is a continuation of application No. 29/733,390, filed on May 1, 2020, now Pat. No. Des. 902,250, which is a continuation of application No. 29/704,999, filed on Sep. 9, 2019, now Pat. No. Des. 883,307, which is a (Continued)

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outermost dashed broken lines in the FIGURE show a display screen or portion thereof, and form no part of the claimed design. The other dashed broken lines in the FIGURE show portions of the graphical user interface that form no part of the claimed design. The dot-dash broken lines in the FIGURE and the areas within the dot-dash lines show portions of the graphical user interface that form no part of the claimed design.

1 Claim, 1 Drawing Sheet
